(57) **CLAIM**

The ornamental design for a safety vest with reflective strips, as shown and described.

DESCRIPTION

FIG. 1 is a front elevation view of a safety vest with reflective strips showing my new design with a vest and a pair of reflective strips;

FIG. 2 is a rear elevation thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is an isometric view thereof.

The broken lines shown in FIG. 2 show unclaimed subject matter only and form no part of the claimed design.
